(57) **CLAIM**

The ornamental design for a storage box for game card, as shown and described.

DESCRIPTION

FIG. 1 is a front and left side perspective view of a storage box for game card, showing my design.

FIG. 2 is a rear and right side perspective view thereof.

FIG. 3 is a front elevational view thereof.

FIG. 4 is a rear elevational view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a perspective view in closed configuration thereof. The broken lines in the drawings depict portions of the storage box for game card that form no part of the claimed design.
